James Boyd,
INVENTOR, By
Charles M. Woodward Atty.

UNITED STATES PATENT OFFICE.

JAMES BOYD, OF ST. PAUL, MINNESOTA.

COMBINED RECEPTACLE AND ADJUSTABLE SEAT.

SPECIFICATION forming part of Letters Patent No. 530,469, dated December 4, 1894.

Application filed February 20, 1894. Serial No. 500,850. (No model.)

To all whom it may concern:

Be it known that I, JAMES BOYD, a citizen of the United States, residing at St. Paul, in the county of Ramsey and State of Minnesota, have invented certain new and useful Improvements in a Combined Receptacle and Adjustable Seat, of which the following is a specification.

This invention relates to combined receptacles and adjustable seats, and consists in the construction, combination, and arrangement of parts, as hereinafter shown and described, and specifically pointed out in the claims.

15 In the drawings, Figure 1 is a perspective view of the combined receptacle and seat, closed, and Fig. 2 is a perspective view of the combined receptacle and seat with the combined seat and cover portion elevated, and 20 turned half way around. Fig. 3 is a cross sectional view with the parts arranged as in Fig. 2. Fig. 4 is a view similar to Fig. 3 illustrating another modification in the construction of some of the parts, the elevated cover 25 and seat in this illustration being shown turned partially around as in Figs. 2 and 3.

A is a receptacle or casing which may be of any suitable size or material, and with a cover B, and in Figs. 3 and 4 shown provided 30 with an internal frame a', and adapted to fit down over the receptacle when placed in its lowermost position, as shown in Fig. 1.

In Fig. 4 the frame a' is shown displaced by a board a² as hereinafter explained.

35 The part B is intended to perform the double function of a cover to the receptacle A and also as a seat, and to make it more completely adapted to that purpose it will be arranged to be adjusted higher and lower, as may be 40 required, and as shown in Figs. 2, 3 and 4.

The cover B is shown swiveled upon a standard D', the latter supported in a socket D² in the interior of the receptacle, the socket being supported by cross partitions E, or other 45 suitable means. By this arrangement the cover B may be raised or lowered to any height, and by arranging the standard to be held at any point of elevation, the "seat" may be likewise held at any point of elevation.

50 In Fig. 3 standard D' is shown secured by its upper end in a "head" b' having arms b² radiating outward and secured to the frame

a', the "head" b' and arms b² forming a "spider frame" by which the cover may be swiveled upon the standard, so that the seat may 55 swing around with the occupant, as in the ordinary swivel chair or "seat."

In Fig. 4 the cover B is shown provided with a wooden lining a² to which the spider frame b' b² is connected, and with a sheet 60 metal lining a³ inside the wooden portion a², the standard D' being cast in one piece with the spider frame. This construction will be employed when sheet iron or other thin metal is employed for the receptacle A and cover B, 65 and will be found the most suitable construction for some forms of the device.

Any desired means may be employed to support the "seat" in its elevated position, but for the purpose of illustration I have 70 shown in Figs. 1, 2 and 3 a simple spring bolt d' adapted to catch by its inner point in one of a series of holes d² in the standard D' at suitable intervals. The uppermost and lowermost of the holes d² are formed with parallel upper and lower edges, so that while the end of the bolt d' rests therein the standard 75 will be immovable until the bolt is released. Thus when the cover is lowered down, as shown in Fig. 1, the bolt entering the upper 80 hole d² will "lock" the cover shut. The intermediate holes d² are formed, as shown with inclined lower edges, so that they will offer no resistance to the elevation of the standard, but will catch the bolt and hold the standard 85 from any downward movement. By this arrangement when the seat is to be elevated it is only necessary to release the bolt d' and draw the seat upward, when it will be held at whichever one of the holes d² the bolt d' 90 enters. When the standard is elevated to a point of sufficient height for the bolt d' to engage with the lowermost hole d², the straight edges of the latter will "lock" the standard and prevent its entire withdrawal from the 95 socket and disengagement from the receptacle, which is a very desirable and necessary provision to prevent the separation of the seat from the receptacle every time an attempt is made to move them from place to place.

The receptacle may be provided with partitions, or left entirely unobstructed, as may be required.

In Fig. 4 I have shown a notched catch bar

h' to support the seat in its different positions, the notched bar adapted to be actuated by a rod *h*² from outside the casing, as shown.

This device will be found very convenient 5 for the use of hunters, fishermen and other sportsmen, to carry their supplies in, and at the same time provide a convenient seat when occasion requires.

When a circular standard *D'* is employed, 10 it will be provided with a groove *e'* into which the inner end of a set screw *e*² will fit, to prevent the standard from revolving in the socket *D*², which would otherwise interfere with the alignment between the holes *d*² and the bolt 15 *d'*. A spring *F'* will preferably be arranged in the standard *D'* to assist in elevating the combined seat and cover *B*. The spring may be arranged as shown at *F*² in Fig. 4, or in any desired form to accomplish the desired 20 result.

A strap handle *K* may be arranged upon the cover *B* to carry the device by when being transported.

Having thus described my invention, what 25 I claim as new is—

1. A receptacle, a standard supported by said receptacle, a frame having a stud fitting said standard, a spring within said standard and adapted to support said stud and frame, said stud having a series of graduated indentations or cavities, and a catch adapted to enter one of said cavities and hold said frame at any required point of elevation, substantially as and for the purpose set forth. 30

2. A receptacle, a standard supported by 35 said receptacle, a frame swiveled upon said standard, a combined seat and cover for said receptacle and supported by said swiveled frame, and means whereby said standard may be adjustably supported upon said receptacle, substantially as and for the purpose set forth. 40

In testimony whereof I have hereunto set my hand in the presence of two subscribing witnesses.

JAMES BOYD.
